DESIGN FOR A SAFETY SWIM SUIT

Leo W. de Crenza, New York, N. Y.

Application December 20, 1948, Serial No. 150,270

Term of patent 3½ years

(Cl. D3—17)

To all whom it may concern:

Be it known that I, Leo W. de Crenza, a citizen of the United States of America, residing in New York city, county of New York, and State of New York, have invented a new, original, and ornamental Design for a Safety Swim Suit, of which the following is a specification, reference being had to the accompanying drawing, forming part thereof, wherein,

Figure 1 is a front elevational view of a safety swim suit, showing my new design with the safety tube portion inflated.

Figure 2 is a rear elevational view of the safety swim suit shown in Figure 1.

Figure 3 is a view similar to Figure 1, showing the skirt section in upturned position, and disclosing the attached pants member.

I claim:

The ornamental design for a safety swim suit, substantially as shown and described.

LEO W. DE CRENSA.
